UNITED STATES PATENT OFFICE.

WILLIAM F. HARRINGTON, OF TOLEDO, OHIO, ASSIGNEE TO THE WILLYS-OVERLAND COMPANY, OF TOLEDO, OHIO, A CORPORATION OF OHIO.

VALVE-OPERATING MECHANISM.

Application filed February 6, 1919. Serial No. 275,464.

This invention relates to internal combustion engines, and particularly to the valve operating mechanism employed for controlling the intake and exhaust valves, which is particularly adapted for use in connection with an internal combustion engine of the V-type.

One object of the invention is to provide a mechanism of the character described which will be entirely enclosed within the casing members.

A further object of the invention is to provide a mechanism of the character described which is particularly applicable for use with internal combustion engines of the V-type, wherein the various valves carried by the several cylinders are operated by a common cam shaft.

A further object of the invention is to provide a mechanism of the character described wherein the several valves are operated from a common cam shaft by means of a plurality of rocker arms, avoiding the use of the pull rods or push rods ordinarily employed.

A further object of the invention is to provide a mechanism of this character, particularly adapted for use in connection with an internal combustion engine of the V-type, wherein the various valves of the several cylinders are operated by a common cam shaft located in substantially the same horizontal plane with the upper portions of the various valve stems.

A further object of the invention is to provide a mechanism for operating oppositely inclined valves of an engine cylinder in such a manner that the thrust impressed thereon will be in a direction in line with the longitudinal axis of each of the several valve stems.

A further object of the invention is to provide a mechanism of this character which is of simple construction and efficient in operation.

Further objects of this invention relate to economies of manufacture and details of construction as will hereinafter appear from the detailed description to follow.

The objects of the invention are accomplished in one instance by the devices and means described in the following specification, but it is evident that the same may be varied widely without departing from the scope of the invention, as pointed out in the appended claims.

A structure constituting one embodiment

of the invention, which may be the preferred, is illustrated in the accompanying drawings, forming a part hereof in which:

Fig. I is a vertical-sectional view of an internal combustion engine of the V-type, taken substantially on the line I—I of Fig. II, illustrating the position of the various operating parts of the valve controlling mechanism.

Fig. II is a top plan view partially in section, taken along the line II—II of Fig. I, illustrating the relative position of the various rocking arms with respect to the cam shaft, and the valves operated thereby.

Fig. III is a vertical-sectional view taken along the line III—III of Fig. II.

Fig. IV is a vertical-sectional view taken along the line IV—IV of Fig. III.

Fig. V is a horizontal-sectional view taken along the line V—V of Fig. III.

In the drawings, similar reference characters refer to corresponding parts throughout the several views, and the sectional views are taken looking in the direction of the small arrows at the ends of the section lines.

Referring to the drawings, the engine comprises cylinders 10 arranged in two rows or series, the cylinders of each row being oppositely inclined with respect to the corresponding cylinders of the opposite row. Cylinder heads 11 are positioned above the cylinders of each row and secured thereto in any well known manner. A top casing section 12 is adapted to extend across the head casing sections, and carries the cam shaft, and the various rocking arms actuated thereby for operating the valves. The top casing section is firmly secured to the cylinder head casings in any suitable manner.

A removable cover 13 is firmly secured to the upper portion of the top casing section, and is capable of removal for the purpose of providing a means of ready access to the cam shaft and the various elements operated thereby. An outer wall 14 surrounds the several cylinders and is spaced therefrom to provide a water jacket space about the cylinders. The head casings carry the usual spark plugs 16, and are provided with the usual intake passages 17 and exhaust passages 18 all communicating with the interior of the cylinders, each of the said intake and exhaust passages is provided with valve seats properly arranged therein at the point where each of the several passages communicates with

the interior of the corresponding cylinder. Positioned within the several intake passages in such a manner as to properly seat upon the valve seat 19 and carried by the casing are intake valves 20, each of which is provided with a valve stem 21 extending upwardly therefrom and terminating in a head portion 22. In a similar manner, each of the exhaust passages is provided with an exhaust valve 23 adapted to seat in the proper manner upon the corresponding valve seat 19, and provided with an upwardly extending valve stem 24 terminating in a head 25. The exhaust passages 18 from the several cylinders comprising one series or row communicate with one of the exhaust manifolds 26.

The lower portion of the top casing section 12 and the upper portion of the cylinder head casing are so constructed as when properly assembled to form a firm support for the top casing and provide means for properly securing the parts together. A cam shaft 27 extends in a direction substantially parallel with the engine crank shaft (not shown), and is adapted to be rotated from the crank shaft in any suitable manner so as to give it a speed of rotation proportionate to that of the crank shaft. The cam shaft 27 carries a plurality of cam elements 28 firmly secured thereto, the said cam shaft being suitably supported in bearings 29 formed in the top casing section 12. The top casing section 12 is provided with portions 30 forming bearings for a pair of shafts 31, which extend in a direction parallel to each other, and to the cam shaft, and are positioned on opposite sides of the cam shaft and in substantially the same horizontal plane therewith. The shafts 31 are adapted to provide bearings for firmly supporting a plurality of upper and lower rocker arms 32 and 33, respectively. The rocker arms 32 and 33 are of similar construction and extend in opposite directions from the cam shaft for a purpose which will be hereinafter described. The top casing section is also provided with a plurality of bearings 34 for suitably supporting a plurality of hollow shafts 35, which also extend in a direction parallel to the direction of the cam shaft and upon opposite sides thereof, they being positioned outwardly with respect to the shafts 31, and each of the said hollow shafts lying substantially in the plane determined by the longitudinal axes of the cylinders comprising one row or series.

Each cylinder is provided with a pair of exhaust valves 23 having stems 24 extending upwardly through the head casing and adapted to slide in bearing sleeves 37 positioned within the head casing. A coiled spring 38 surrounds the upper portion of each of the valve stems 24 and bears at its lower end against the head casing, and at its upper end against a cup-shaped washer 39 carried by the valve stem. In a similar manner each

of the cylinders is provided with a single intake valve 20 provided with a valve stem 21 extending upwardly through the head casing and slidably mounted in a bearing sleeve 40 secured therein. Each of the several valve stems 21 is surrounded by a coiled compression spring 42, the lower end of which is adapted to bear against a portion of the head casing, the upper end bearing against the under surface of a cup-shaped washer 43, secured to the upper end of the valve stem. Revolvably mounted upon each of the hollow shafts 35 at a point directly above each of the cylinders 10 is a sleeve 44 provided with a pair of integral arms 45 extending therefrom in a direction towards the cam shaft, and positioned in such a manner that the inner ends of the arms 45 extend over and are adapted to rest upon the heads 25 of the two valve stems 24 with which the exhaust valves 23 of each cylinder are provided. Each of the sleeves 44 is provided with an enlarged portion substantially centrally thereof, which serves as a housing for a sleeve 46 adapted to be positioned therein and revolvably mounted upon the hollow shaft 35. Each of the sleeves 46 is provided with a pair of arms 47 and 48 adapted to extend in opposite directions therefrom, the said arm 48 being designed to extend outwardly from the shaft 35 in such a manner that its outer end will overlie and contact with the head 22 of the valve stem 21 carried by the intake valve 20 of the cylinder. The enlarged portion 49 of the sleeve 44 is provided with diametrically opposite openings 50 for the reception of the arms 47 and 48, said openings being of such size as to permit a suitable rotative movement of the sleeve 46 and arms 47 and 48 carried thereby with respect to the sleeve 44.

Each of the upper and lower rocker arms 32 and 33 respectively is provided with bearing portions 52, positioned near the central portion of the rocker arms and adapted to be rotatably mounted upon one of the shafts 31 in such a manner as to permit the rocker arms to oscillate thereon upon rotation of the cam shaft. Each of the upper rocker arms 32 is positioned in such a manner that its inner end overlies the cam shaft and has secured thereto a roller 53 adapted to contact with one of the cam elements carried by the cam shaft in such a manner as to oscillate the rocker arm upon rotation of the cam shaft. In a similar manner each of the lower rocker arms 33 is rotatably mounted upon the corresponding shaft 31 and has its inner end extending to a position beneath the cam shaft, the said inner end of each rocker arm 33 being provided with a roller 54 adapted to contact with and be actuated by one of the cam elements carried by the cam shaft for the purpose of communicating oscillatory movement to the lower rocker arm. The outer end of each of the upper rocker arms 32 is adapted to overlie and

rest upon the inner end of one of the arms 45 carried by the sleeve 44, in such a manner that when the inner end of the rocker arm 32 is raised by one of the cam elements the outer 5 end of the rocker arm will be depressed, thus forcing downwardly the arms 45 and the corresponding valve stems 24 secured to the two exhaust valves 23, for the purpose of permitting exhaust of the combustion gas from 10 the cylinders. The outer end of each of the lower rocker arms 33 is positioned beneath and adapted to contact with the end of the inwardly extending arm 47 secured to the sleeve 46.

15 When each of the lower rocker arms is oscillated by the cam element 28 on the cam shaft co-operating with the roller 54 upon the inner end of the rocker arm; the outer end of said arm will be correspondingly raised 20 whereby the sleeve 46 will be oscillated and the arm 48 will press upon the head 22 of the valve stem carried by the inlet valve of the cylinder to open the valve and permit fuel to be drawn into the cylinder.

25 It will be noted that the arms 45, 47 and 48 provide a plurality of valve operating rocker arms pivotally positioned along a line extending substantially midway between and slightly above the upper ends of the oppositely inclined valve stems carried by the inlet and exhaust valves of each cylinder respectively. By this construction the pressure exerted upon each valve for the purpose of 30 opening the same is applied in a direction axially of each valve stem, thus preventing any binding of the valve stem in the sleeve.

The cam shaft is rotated from the main crank shaft of the engine in any suitable manner for maintaining the speed of rotation 40 of the cam shaft proportionate to the speed of rotation of the crank shaft. Upon the rotation of the cam shaft in its bearings 29 the cam elements carried thereby act against the inner end of the upper and lower rocker arms to oscillate the same at regular intervals 45 in the rotation of the cam shaft. As the upper and lower rocker arms are oscillated, their outer ends contact with the valve operating rocker arms, in the manner previously described, whereby the valve operating rocker 50 arms are correspondingly oscillated upon the hollow shaft 35, thus exerting pressure upon the upper ends of the several valve stems for the purpose of opening the corresponding 55 valves at regular intervals to admit fuel to the cylinders and permit the escape of the combustion products therefrom.

While I have shown and described in considerable detail a specific embodiment of my invention, it is to be understood that this showing and description is illustrative only and for the purpose of rendering my invention more clear, and that I do not regard the invention as limited to the details of construction illustrated or described, nor any of them,

except in so far as I have included such limitation within the terms of the following claims, in which it is my intention to claim all novelty inherent in my invention broadly as well as specifically.

What I claim as new and desire to secure by Letters Patent is:

1. In an internal combustion engine, a plurality of cylinders arranged in rows, a cam shaft, oppositely inclined inner and outer 70 valves carried by the cylinders, valve operating rocker arms one for each valve having their axes of rotation in alignment and located between the oppositely inclined valve stems, and means operated by the cam shaft 75 for actuating said rocker arms.

2. In an internal combustion engine, a plurality of cylinders arranged in rows, inner and outer valves carried by each cylinder and having their stems inclined with respect to 80 each other, valve operating rocker arms for both valves having their axes of rotation in alignment and located between the oppositely inclined valve stems, and means including 85 rocker arms and a common actuating member between said rows for operating said first arms.

3. In an internal combustion engine, a plurality of cylinders, a plurality of valves carried by each cylinder, a cam shaft, sets of upper and lower rocker arms extending in opposite direction therefrom, each set of upper and lower rocker arms being rotatable about a common axis and having portions adapted to engage the upper and lower surfaces of 90 the cam shaft respectively and a plurality of 95 rocker arms for each cylinder having aligned axes, actuated by said upper and lower rocker arms for operating the valves.

4. In an internal combustion engine, a plurality of cylinders, a plurality of valves carried by each cylinder, a cam shaft, upper and lower rocker arms extending in opposite directions from the cam shaft, the rocker arms for the valves of each cylinder having a common axis of rotation, and means actuated by 100 said arms for operating said valves in regular succession.

5. In an internal combustion engine, a plurality of cylinders, a plurality of valves carried by each cylinder, a cam shaft, upper and lower rocker arms extending in opposite directions from the cam shaft, the rocker arms on each side of the cam shaft having a common axis of rotation, and separate valve operating 115 rocker arms actuated by each of said upper and lower rocker arms for operating 120 the valves in regular succession.

6. In an internal combustion engine, a plurality of cylinders, inner and outer valves carried by each cylinder and having their stems inclined with respect to each other, valve operating rocker arms located between the opposite inclined valve stems of each cylinder and having a common axis, a cam 125 130

shaft, and upper and lower rocker arms on each side of the cam shaft for actuating the valve operating rocker arms, the upper and lower rocker arms on each side of the cam shaft having their axes of rotation in alignment.

7. In an internal combustion engine, a plurality of cylinders, inner and outer valves carried by each cylinder and having their stems inclined with respect to each other, valve operating rocker arms located between the oppositely inclined valve stems and having a common axis of rotation, a cam shaft, and upper and lower rocker arms extending in opposite directions from the cam shaft and adapted to actuate the said valve operating rocker arms in regular succession upon rotation of the cam shaft.

8. In an internal combustion engine, a plurality of cylinders, inner and outer valves carried by each cylinder and having their stems inclined with respect to each other, valve operating rocker arms having their axes of rotation in alignment, and located between the opposite inclined valve stems, a cam shaft, and upper and lower rocker arms extending in opposite directions from the cam shaft, the upper and lower rocker arms on each side of the cam shaft having their axes of rotation in alignment, said upper and lower rocker arms being adapted to actuate the valve operating rocker arms in regular succession upon rotation of the cam shaft.

9. In an internal combustion engine of the

V-type, a cam shaft extending longitudinally of the engine and located between the two rows of cylinders, inlet and exhaust valves for each cylinder, separate rocker arms pivotally mounted between the inlet and exhaust valves for actuating the same, and means actuated by the cam shaft for operating the separate rocker arms.

10. In an internal combustion engine having a plurality of cylinders arranged in parallel rows, inlet and exhaust valves carried by the cylinders of each row, a cam shaft located between the rows of cylinders, rocker arms extending in opposite directions from the cam shaft, and valve operating rocker arms adapted to be actuated by the first named rocker arms for operating the inlet and exhaust valves.

11. In an internal combustion engine, a plurality of cylinders, an inlet valve for each cylinder, a plurality of exhaust valves for each cylinder, a common engine driven cam shaft, rocker arms contacting with said cam shaft and projecting in opposite directions therefrom, two sets of valve rocker arms operated by said first mentioned rocker arms, each set of valve rocker arms being rotatable about a common axis, certain of said valve rocker arms being adapted to actuate the inlet valves and certain others being adapted to operate the plural exhaust valves of each cylinder simultaneously.

In testimony whereof, I affix my signature.
WILLIAM F. HARRINGTON.
